(Cl. D58—11)

To all whom it may concern:

Be it known that I, Henry A. Van Gestel, a citizen of the United States, residing at Brookline, county of Norfolk, State of Massachusetts, have invented a new, original, and ornamental Design for Confectionery Packages, of which the following is a specification, reference being had to the accompanying drawings, forming a part thereof.

Fig. 1 is a front perspective view of a confectionery package embodying the design, being taken from a point slightly above the package.

For better illustration of the surface ornamentation features of the design of Fig. 1, Fig. 2 shows the wrapper of the package in flat position as it appears before it is applied to the package.

The characteristic features of the design are shown in Fig. 1.

I claim:

The ornamental design for a confectionery package substantially as shown and described.

HENRY A. VAN GESTEL.
